UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

MACHINE FOR TREATING LEATHER AND SIMILAR MATERIALS.

1,170,504.

Specification of Letters Patent.

Patented Feb. 8, 1916.

Application filed July 7, 1910. Serial No. 570,769.

To all whom it may concern:

Be it known that I, ARTHUR BATES, a subject of the King of England, residing at Leicester, Leicestershire, England, have invented certain Improvements in Machines for Treating Leather and Similar Materials, of which the following description, in connection with the accompanying drawings, is a specification, like reference characters on the drawings indicating like parts in the several figures.

This invention relates to shoe machinery, and is of particular utility when embodied in a machine for beveling pieces of leather for use in forming soles, although I contemplate the utilization of my improvements in any field for which they are adapted by their nature.

An important object of my invention is to provide a machine for beveling articles such as soles, having an operating device, such as a knife, and actuating mechanism therefor which may be run substantially continuously, with means to connect the actuating mechanism with the operating device actuatingly at times, the means to accomplish this connection being preferably set in train by insertion of the material for the beveling operation, and for this purpose I prefer to construct and arrange this means to act as a work gage, limiting its range of movement prior to the beveling operation so that it will serve as a firm rest for the workpiece during the operation, and providing for its adjustment to present the workpiece in such a position that the minimum of waste material will be cut off.

Another object of importance is the provision of means to clear this gage automatically from the path of the material removed from the workpiece, so that the material cut away can be discharged freely, this release being timed so that the workpiece will be properly supported, preferably by the knife, when the work gage has been cleared away, so that the beveled part will be clean-cut throughout; also means to reset the workgage automatically in predetermined position prior to each beveling operation.

A further object is to provide a front shear member for coöperation with the knife, so constructed and arranged that it may be adjusted with nicety to present its

edge in proper alinement with the plane of operation of the knife, and for purposes of this and other adjustments I prefer to mount the front shear in a support rotatable about the cutting edge as an axis, in order to permit variation in the angle of bevel by presenting the material to be treated in desired angular relation to the plane of operation of the knife.

Still another object of notable importance is to insure actuating engagement of the actuating mechanism with the operating device at a suitable, predetermined point in the cycle of movement of the actuating mechanism, and in order to provide compact means to this end I have devised a two-part member with an energy storage device interposed between the parts, one of these parts serving as the gage heretofore mentioned and transmitting the energy received by it, from the insertion of the sole, or other workpiece, to the energy storage device, by which it is eventually transmitted to the other part and utilized to effect relative movement of the operating device and actuating mechanism into actuating relation, eventuating, at the proper phase of the cycle, in actuating engagement. The energy storage device may also serve conveniently as the means for resetting the gage automatically.

Among other objects of my invention is the provision of a latch or retainer acting positively to control the shipper part of the two-part member, and means acting at regular intervals to trip the latch and release the shipper part, which can only effect the connection of the actuating mechanism with the operating device during such periods of release, and only then at such times as the shipper is subjected to the influence of energy stored by the gage in the energy-storage device upon emplacement of the work-piece for the beveling operation; and the safeguarding of the hands of the operator from mutilation by the knife constitutes a noteworthy object of my invention.

The various features of my invention will be illustrated and described fully in the accompanying drawings and specification and pointed out in the claims.

In the drawings:—Figure 1 is a front view of a machine in the construction of

which my improvements have been embodied, this view being taken in the direction of the arrow, Fig. 2. Fig. 2 is a vertical, longitudinal, sectional view on the line $x^2 x^2$, Fig. 1, looking from left to right; and Fig. 3 is a fragmentary view similar to Fig. 2, showing in another position the parts particularly concerned with the present invention.

10 In the embodiment of my invention selected for illustration and description to enable ready and complete understanding of my improvements, the part designated by the reference numeral 1 is the operating device, which may be of any suitable character, and in the instance illustrated herein is shown as a knife, preferably constructed and arranged to coöperate with a fixed shear member 2, to bevel, or perform a similar operation upon, a sole or like workpiece 3. For this purpose the knife 1 is shown as secured adjustably, by a screw 4, upon a sliding carrier 5 mounted in ways 6 supported by the sidepieces 7 of a suitable frame, which supports also a member 8, rotatable about a transverse axis lying in the plane of operative movement of the knife 1, and carrying the front shear 2, being preferably constructed and arranged to permit 25 adjustment of the shear 2 to bring its edge 2^x into exact registry with the axis of rotation, so that whatever may be the angular position to which the shear 2 is brought by rotation of the member 8 to determine the 30 position in which the workpiece 3 shall be presented to the knife to secure the desired angle of bevel, the edge 2^x of the front shear will always be presented properly adjacent to the plane of operative movement of the 35 knife 1. Suitable means may be provided, such as the bolts 9 to hold the shear 2 in adjusted position with its edge directly upon the axis of the member 8 and in alinement with the cutting edge of knife, and a clamp 40 10 to hold the member 8 in adjusted rotative position.

As one convenient form of means to actuate the cutter 1, I have shown a shaft 12, provided with a fast pulley 13, acting also 45 as a fly-wheel, and a loose pulley 14, the rotary motion of the shaft being transmitted to the cutter by means 15 suitable to reciprocate the latter, and taking the 50 form of an eccentric, in the instance illustrated, having a floating end 16 adapted to be engaged at times with a knife-carrier 5, as by a forked portion 17 upon the floating end presented in position to receive the suitably formed part 18 of the carrier, when 55 the floating end reciprocates in alinement therewith. The part 18 may be formed separately and secured to the part 5 by suitable means, as by the screw 18^x shown in Fig. 2. The actuating position of these 60 parts is best shown in Fig. 3, wherein the

knife 1 has just completed its cutting stroke, under the thrust of the forked floating end 17 of the eccentric, and upon further rotation of the shaft the eccentric will be withdrawn, and the operating parts will assume 70 the relative position shown in Fig. 2, under the action of the several instrumentalities I will now describe, the position of Fig. 2 being the normal, inoperative position of the parts when ready for operative emplacement 75 of the workpiece 3, by the downward pressure of which, in accordance with an important feature of my invention, the machine is set in operation. Accordingly, I have shown at 20 a device for engagement 80 with the workpiece 3, and of any suitable form to be moved by it to release the actuating mechanism for the knife 1, the device comprising, in the preferred embodiment of my invention, a two-part member including 85 a lever 21, rotatably mounted upon a cross-rod 23 of the frame, and a coöperating lever 24 mounted also upon the rod 23, with means 25 interposed between the levers and tending normally to hold them in the position 90 shown in Fig. 2, with the portion 20 of the device presented below, and to act as a rest or gage for, the workpiece 3, which may be fed vertically from above.

The positioning means 25 may be of any 95 suitable sort, and as one convenient form of such means I have shown (see Fig. 2) a coil spring 25 held under compression within a hollow plunger 26 entering a socket 27, against the base of which the spring is 100 seated, while the free end of the plunger 26 is engaged with a knuckle 28 of the lever 21, tending to rotate the levers 21 and 24 in opposite directions upon the rod 23, such rotation being preferably limited adjustably by suitable means, such as the set-screw 29 carried at 30 by the knuckle 28 of the lever 21, and bearing against a short arm 31 of the lever 24. This screw serves as a convenient form of means to regulate the position 105 of the gage 20 relatively to the plane of operation of the knife, and therefore the amount of material cut from the sole, and it will be seen upon reference to Figs. 2 and 3 that when the gage has been located properly, the workpiece 3 will be held with its front lower corner closely adjacent to the cutting axis 2^x and the knife 1 will therefore pass through that corner of the workpiece, wasting a minimum of material, as 110 shown at 3^x in Fig. 3.

The long lever arm 24 is extended, preferably, as at 32, rearward and upward into position to be engaged with, and to control the operation of, the floating end 16 of the 115 eccentric, an antifriction roller 33 being preferably interposed therebetween, and when permitted so to do, the effect of the spring 25 is to hold the lever arm 32 and the floating end 16 upward, as in Fig. 3, with the 120

forked part 17 ready to engage the part 18 when the floating end 16 of the eccentric moves forward. Suitable means may be provided to hold the floating end 16 toward the arm 32, as, for example, the spring 39, (see Fig. 2). Normally, however, I prefer that the arm 32 shall be held positively downward, in the position shown in Fig. 2, permitting the spring 39 to hold the floating end 16 of the eccentric out of the plane of the carrier 5, so that the eccentric normally reciprocates freely below the carrier, the roller 33 running back and forth upon the arm 32 as a track. Any suitable means may be provided to hold the arm thus, and I have shown as one convenient device for this purpose a latch 40 (best seen in Fig. 3) mounted upon a bearing stud 41 supported loosely by the frame, the latch being shown as connected with the stud by a sleeve 42 and set screw 43, and to actuate the latch suitable means may be provided, for which purpose I have shown a trip lever 44 formed with the latch 40 and projecting into the path of the roller 33, the latch having also a part 45 to be engaged with a hook 46 on the lever 32, holding the same normally as shown in Fig. 2. A lip 45* may be provided to serve as one suitable form of means to direct the hook 46 into proper engagement with the holding part 45.

The latch 40 is preferably drawn normally into this position for catching engagement by suitable means 47, shown (see Fig. 3) as a spring secured to the frame at 48, and as the floating end 16 of the eccentric reciprocates with each turn of the shaft 12 the roller 33 throws out the latch 44-40 and releases the hook 46 and its arm 32, but the latter does not rise to the position of Fig. 3 unless and until the spring 25 is placed under compression by rotation of the arm 21 under the action of the workpiece 3 upon the rest 20.

In operating my improved machine, the sole 3 is thrust down against the rest or gage 20 with a steady pressure sufficient to rotate the lever 21 upon the rod 23, a slight movement from the position shown in Fig. 2 serving to bring the lower edge of the workpiece level with the cutting edge 2*, and to compress the spring 25, storing energy therein until the floating end 16 of the eccentric 15 is moved forward by rotation of the shaft 12, and the roller 33 trips the lever 44 and latch 45, releasing the hooked end 46 of the lever 32 and permitting the latter to be raised by the energy stored in the spring 25 (see Fig. 2), which exceeds in strength that of the spring 39, being sufficient to raise the floating end 16 of the eccentric to the level of the knife carrier part 18, as shown in Fig. 3, which represents the parts in engagement as they will be upon the next forward reciprocation of the eccentric. The knife is then

thrust forward by the eccentric, and cuts off a minimum wastepiece of sole such as that shown at 3* in Fig. 3, and in order to give clearance for this severed bit, the member 20 may be, and preferably will be, moved farther downward in accordance with an important feature of my invention, by suitable means, as by the engagement of an abutment 202 on the lever 21 with a roll 55 upon the carrier 5, the latter serving to turn the lever 21 upon its bearing rod 23 into the position shown in Fig. 3, leaving ample clearance for discharge of the bit 3*. The operation of these parts is preferably timed so that the workpiece 3 will be supported by the gage 20 until the knife 1 has advanced sufficiently through the material to insure the proper support thereof by the knife during the remainder of the cutting stroke, and thus the bevel will be clear-cut throughout. This completes the operation, the beveled sole 3 may be withdrawn, and when the eccentric 15 is withdrawn by the continued rotation of the shaft 12, the fork 17 will retire from the carrier part 18, the spring 39 will pull down the floating end 16 and lever arm 32 (see Fig. 2) and the spring 47 will fasten the latch 45 upon the hook 46 and hold the lever arm 24 down each time the eccentric end 16 moves forward until the fork 17 is past its point of possible engagement with the part 18 of the knife-carrier, except at such times as the compression of the spring 25 by the lever 21, under the action of the sole 3, applies its stored energy to turn the lever 24 and raise the lever 32 and floating end 16 into the position of Fig. 3. The retraction of the carrier 5 to the position shown in Fig. 2, ready for another operation, may be accomplished by any suitable means, as by a spring 56 (see Fig. 1), and suitable means, such as the thrust bolts 57, may be provided to hold the knife 1 up to its work in adjusted position. The rearward movement of the carrier may also be limited suitably, as by a screw 58, (see Fig. 1).

In order to avoid mutilation of the fingers of operatives, I prefer to provide a suitable guard, such as that shown at 50 in Fig. 2, having a lip 51 brought down in approximately vertical position near the front end of the knife, and forming with the front shear 2 an upright work-passage just wide enough to permit easy introduction of the workpiece 3.

Having illustrated and described my invention thus fully, and suitable means by which the same may be carried into effect, I wish it understood that I do not limit myself to the specific materials and form of construction selected for description herein, nor do I limit myself in general otherwise than as set forth in the claims read in connection with this specification.

Having described my invention, what I

claim as new and desire to secure by Letters Patent of the United States is:—

1. A machine for beveling material for the soles of shoes; comprising a knife; actuating mechanism therefor, having a given cycle of operation; and means operable by the work to cause the actuation of said knife by said mechanism at a predetermined point in said cycle.
2. A machine for beveling material for the soles of shoes; comprising a reciprocating operating device; actuating mechanism therefor and normally unconnected therewith; and a work-gage in each instance displaceable by the work to connect said device and mechanism operatively, said work-gage in each instance including a yielding connective member.
3. A machine of the class described; comprising an operating device; actuating mechanism therefor; a controlling device operable by the work to control the actuation of said operating device by said actuating mechanism; and means to clear said controlling device automatically from the path of said work.
4. A machine of the class described; comprising an operating device; actuating mechanism therefor; a member displaceable yieldingly by the work to start the actuation of said device by said mechanism; means to retard said displacement so as to constitute said member a work-gage; and means acting subsequently to move said member clear of the work.
5. A machine of the class described; comprising a knife; actuating mechanism therefor; a gage to be engaged with the work to position the same for treatment by said knife, and movable by said work to initiate the operation of said knife by said actuating mechanism; means to clear said gage from the path of the material cut from said work; and means to reset said gage automatically after the cutting operation.
6. A machine of the class described; comprising an operating device to remove material from a workpiece; a yielding work-gage connected with, and to control the operation of, said operating device; and means to move said workgage from engagement with the work to permit the material cut therefrom to fall out of place.
7. A machine of the class described; comprising an operating device; a member to resist lateral displacement of the workpiece under the action of said operating device; a workgage to position said workpiece for operation at the desired region; and means to clear said workgage from the path of said workpiece when the latter is supported by said operating device, said clearance being initiated substantially in the direction of movement of said workpiece.
8. A machine of the class described; com-

prising a shear; a knife operable co-operatively therewith, being movable past the cutting edge thereof at an angle thereto; a workgage to present the workpiece for the beveling action of said knife; and means to withdraw said workgage for clearance of the waste from said workpiece, said means being constructed and arranged to act when said knife shall have advanced partly into the work into position to support said workpiece for the remainder of said beveling stroke.

9. A machine of the class described; comprising a knife and its carrier; an oscillating work-engaging member; and means to support said work engaging member in position to present the workpiece to be operated upon by said knife; said work engaging member being constructed and arranged to be engaged by said carrier at times, and rotated thereby to clear said work engaging member from the path of the waste cut from said workpiece by said knife, said clearance being initiated substantially in the direction of movement of said workpiece.

10. A machine of the class described; comprising an operating device; actuating mechanism therefor; and a controlling device including a two-part member constructed and arranged to be engaged, one part with the work and having means to store energy when so engaged and moved, the other part of said member being connected with said actuating mechanism and arranged to initiate the actuation of said operating device thereby when the energy stored in said member is released.

11. A machine of the class described; comprising an operating device; actuating mechanism therefor; a controlling device including a two-part member constructed and arranged to be engaged, one part with the work and having means to store energy when so engaged and moved, the other part of said member being connected with said actuating mechanism and arranged to initiate the actuation of said operating device when the energy stored in said member is released, and a retainer for said part and means to trip said retainer at times to release the energy stored in said part.

12. A machine of the class described; comprising an operating device; an actuating member reciprocable adjacent to the path of said operating device and movable transversely of its direction of actuating movement into position to be engaged actuatingly with said device; a two-part controlling member, one part of which is adapted to serve as a shipper and be engaged with said reciprocable member to impart said transverse connective movement thereto; said other part being adapted to be engaged with the work for movement thereby; means intermediate said parts to store the energy

generated by movement of said latter part, and adapted to communicate said energy to said shipper part to shift said actuating member transversely; means acting normally to hold said shipper part and said actuating member out of actuating position; and means to trip said holding means from time to time to permit said stored energy to become effective to shift said actuating device into actuating position.

13. A machine of the class described; comprising an operating device, including a knife, and its sliding carrier; an actuating shaft; an actuating eccentric thereon having a floating actuating portion movable transversely into the operating path of said device at times, for actuating reciprocatory engagement therewith; a shipper lever to move said floating portion transversely; a latch to prevent said transverse movement; and a lever to be engaged with said reciprocating parts to trip said latch periodically; and a gage lever having a part to be engaged with the work, when the latter is presented for treatment by said knife, and connected with said shipper lever by a compression spring; said gage lever being constructed and arranged to be moved primarily by said work to store energy in said spring and secondarily by one of said reciprocable parts to clear said work; the energy stored in said spring acting prior to subsequent actuating reciprocation of said floating end to shift said floating end transversely into actuating position.

14. A machine of the class described; comprising a shear; a cutting device reciprocable relatively thereto; a support for said operating parts, said support including a member carrying said shear and rotatable

into different angular positions relatively to said cutting device; and a yielding work gage operable in the respective angular positions of said shear.

15. A machine of the class described; comprising a shear; a cutting device reciprocable relatively thereto; a support for said operating parts, said support including a member carrying said shear and rotatable into different angular positions relatively to 45 said cutting device, the axis of said member lying adjacent to the plane of operation of said cutting device; and means to adjust said shear to said axis; and a yielding work gage operable in the respective angular positions of said shear.

16. A machine of the class described; comprising a shear; a cutting device reciprocable relatively thereto in a plane at an angle to the vertical; and a support for said operating parts; said support including a member carrying said shear and rotatable into different angular positions relatively to said cutting device, the axis of said member being horizontal and lying adjacent to the 65 plane of operation of said cutting device; and means to adjust said shear to said axis, and to secure said member and shear in adjusted position, respectively; said parts serving to permit the introduction of a 70 workpiece from above said cutter, and operation upon said workpiece in upright position.

In testimony whereof I have signed my name to this specification in the presence of 75 two subscribing witnesses.

ARTHUR BATES.
